(57) **CLAIM**

The ornamental design for a case for electronic device, as shown and described.

DESCRIPTION

FIG. 1 is a perspective view including a rear, top, and side of a case for electronic device showing our new design in a first embodiment;

FIG. 2 is a perspective view including a front, top, and side thereof;

FIG. 3 is a perspective view including a rear, bottom, and side thereof;

FIG. 4 is a perspective view including a front, bottom, and side thereof;

FIG. 5 is a rear elevation view thereof;

FIG. 6 is a front elevation view thereof;

FIG. 7 is a side elevation view thereof;

FIG. 8 is an opposite side elevation view thereof;

FIG. 9 is a top plan view thereof;

FIG. 10 is a bottom plan view thereof;

FIG. 11 is a perspective view including a rear, top, and side of the case for electronic device in a second embodiment;

FIG. 12 is a perspective view including a front, top, and side thereof;

FIG. 13 is a perspective view including a rear, bottom, and side thereof;

FIG. 14 is a perspective view including a front, bottom, and side thereof;

FIG. 15 is a rear elevation view thereof;

FIG. 16 is a front elevation view thereof;

FIG. 17 is a side elevation view thereof;

FIG. 18 is an opposite side elevation view thereof;

FIG. 19 is a top plan view thereof; and,

FIG. 20 is a bottom plan view thereof.

The broken lines in the drawings depict portions of the case for electronic device that form no part of the claimed design.
